Term of patent 14 years

(Cl. D66—3)

FIG. 1

FIG. 4

FIG. 2.

FIG. 3.

FIGURE 1 is a perspective view of an overhead railway track unit, showing my new design with portions broken away to indicate indeterminate length;

FIGURE 2 is a fragmentary, enlarged bottom plan view thereof;

FIGURE 3 is a fragmentary, enlarged sectional view taken from either end of FIGURE 2; and,

FIGURE 4 is a fragmentary perspective view thereof. This application is a division of my application Serial No. D. 57,694, filed September 25, 1959.

The side not shown is a mirror image of the side shown. The top is substantially plain.

I claim:

The ornamental design for an overhead railway track unit, substantially as shown and described.
